DESIGN FOR A SEAL PRESS OR SIMILAR ARTICLE

Marshall H. Jackson and Warren Jackson, River Forest, Ill., assignors to Dwight & M. H. Jackson, Chicago, Ill., a corporation of Illinois

Application September 2, 1938, Serial No. 79,699

Term of patent 14 years

To all whom it may concern:

Be it known that we, Marshall H. Jackson and Warren Jackson, citizens of the United States, residing at River Forest, in the county of Cook and State of Illinois, have invented a new, original, and ornamental Design for a Seal Press or Similar Article, of which the following is a specification, reference being had to the accompanying drawing, forming part thereof, wherein

Fig. 1 is a top view of a seal press embodying our new design;

Fig. 2 is a side elevational view of such a press; Fig. 3 is a front elevational view of such a press; and

Fig. 4 is a rear elevational view of such a press.
We claim:

The ornamental design for a seal press or similar article, substantially as shown.

MARSHALL H. JACKSON.
WARREN JACKSON.
